UNITED STATES PATENT OFFICE.

WILLIAM A. BERNARD, OF NEW HAVEN, CONNECTICUT, ASSIGNOR TO THE WILLIAM SCHOLLHORN COMPANY, OF NEW HAVEN, CONNECTICUT.

HAND TOOL.

Application filed April 4, 1921. Serial No. 458,224.

To all whom it may concern:

Be it known that I, WILLIAM A. BERNARD, a citizen of the United States, residing in the city and county of New Haven, State of Connecticut, have invented certain new and useful Improvements in Hand Tools, of which the following is a full, clear, and exact description.

This invention relates to hand tools and has special reference to tools having lever handles which are connected to the operating jaws of the tool in such a manner that the latter are mounted for parallel movement, although some features of the invention are applicable to tools of other types.

The tool which I have illustrated herein has its working jaws formed particularly for the purpose of crimping or compressing an explosive cap or a sheet metal union upon a fuse or the like. Various tools have been constructed for this purpose in the past, but so far as I am aware, there has been no tool provided which will compress the cap casing tightly around the fuse and squeeze the excess portions of the casing into crimps or plaits which will be formed uniformly upon opposite sides of the cap or like part.

One object of my invention is the provision of a hand tool of the plier type which will effectively compress or swage an explosive cap about a fuse in such a manner that the periphery of the fuse will be tightly engaged by the surface of the cap and the excess portions thereof will be drawn out upon opposite sides in the form of plaits.

Another object of my invention is the provision of a hand tool of the character described which will exert pressure upon both sides of an explosive cap at the extremities of a diameter thereof, so that the material upon each side of this diameter will be pressed tightly into engagement with the adjacent portion of the fuse and the excess of the material of the cap upon that side of the diameter will be drawn out in the form of plaits.

A still further object of my invention is to provide a stop for limiting the movement of the work longitudinally of the jaws, so that the same may be more readily positioned within the working surface of the jaws.

Another object of my invention is to provide a novel means for locking the jaws of the tool in closed position when it is desired

to discontinue the use of the same, so that the tool may be more easily carried in the pocket.

To these and other ends the invention consists in the novel features and combinations of parts to be hereinafter described and claimed.

In the accompanying drawings.

Fig. 1 is a side elevational view of a hand tool embodying my improvements; 65

Fig. 2 is a top plan view of the same;

Fig. 3 is an enlarged sectional elevational view of the jaws upon the line 3—3 of Fig. 2;

Fig. 4 is a view similar to Fig. 3, but 70 showing the jaws in closed position;

Figs. 5, 6, 7 and 8 are detail elevational views showing the various steps in the operation of the tool when an explosive cap is being crimped upon a fuse; and 75

Fig. 9 is a sectional view on line 9—9 of Fig. 8, the finished work, however, being shown in elevation.

While I have chosen to illustrate a preferred form of my invention as embodied in a tool particularly adapted for the crimping of an explosive cap upon a fuse or the like, it will be understood that various features are applicable to devices of other kinds, for example, the stop used for positioning the work between the jaws and the novel catch for holding the jaws in closed position might be used upon tools of various kinds. It will also be understood that the particular form of working jaws shown in connection with the tool illustrated herein may also be advantageously used for crimping a union upon a fuse, so that two fuse lengths may be joined together thereby. 85

With reference to the drawing, the tool 95 comprises the lever handles 10 and 11 which are pivoted together at 12 and each of which is connected forwardly of the pivot 12 to one of the jaws 13 and 14 by the pivot pins 15 and 16. The jaws are slotted at their rear ends, as shown at 17 and 18, in dotted lines in Fig. 3, so as to receive the pins 19 and 20 upon the handle members 10 and 11, which is the usual and well-known method of providing parallel movement of the jaws 100. to which, per se, no claim is made in this application.

A coiled spring 21 is connected at one end to the rear portion of one of the jaws and at its other end is connected to the handle 110

member 11, so that the tension of this spring will tend to retain the jaws in open position, as shown in Figs. 1 and 3. The connections between the spring and the lever 5 handle and jaw may be of any desired type, such for instance as is shown in my prior Patent No. 1,229,213, granted June 12, 1917. A pin 22 is set in one of the jaws 14 and projects from the face of this jaw, so that it 10 will be received within a clearance opening 23 within the jaw 13. The pin is provided near its upper end with an annular recess 24, which is adapted to be engaged by the bifurcated end 25 of a slide catch 26, which is movably mounted upon the jaw 13. The slide 26 is provided with a slot 27 disposed longitudinally thereof through which is passed a screw 28 threaded into the outer surface of the jaw 13. Provision is 15 thereby made for the sliding catch 26 to be moved longitudinally of the jaw 13. To prevent pivotal movement of this catch about the pin 28, a pair of lugs 29 are struck from the sides of the catch 26 and are disposed 20 upon opposite sides of the jaw 13. The catch is provided with a rear upturned end 30, which may be engaged by the thumb or finger of the operator of the tool to slide this catch longitudinally of the jaw upon 25 which it is mounted and into engagement with the recess 24 in the upper end of the pin 23 when the jaws are in closed position. As shown in Fig. 4, at this time, the pin projects slightly beyond the outer surface of 30 the jaw 13 so that the recess is in position to be so engaged.

The jaws 13 and 14 are provided with working surfaces in the form of transversely directed substantially semi-cylindrical recesses 31 and 32, which when the jaws are 40 closed, as shown in Fig. 4, will together form a substantially cylindrical opening therebetween. This opening, as shown in Fig. 9, is preferably slightly smaller in diameter than the fuse about which the cap 45 is to be crimped.

The operation of the tool is shown more especially in Figs. 5 to 9 in which an explosive cap 33 and a fuse 34 are shown 50 between the jaws in position to be operated upon thereby. As shown in Fig. 5, the end of the fuse is placed within the cap and the portion of the cap to be crimped is inserted between the jaws and moved toward the pivot 12 until it contacts with the stop pin 22. This will position the cap and fuse adjacent the working openings 31 and 32, so that when the jaws of the tool are brought together, the cap will lie within these two 55 recesses. The position of the cap and fuse when the jaws first are brought into contact therewith is shown in Fig. 6 when they assume a correct position within the working surfaces of the jaws. Further movement 60 of the two jaws tends to cause the wall of

the cap to fill the semi-cylindrical transverse recesses provided in the jaws of the tool, which will cause the cap which has heretofore been cylindrical in shape to assume an elliptical shape, as shown in Fig. 7. 70

It is clearly brought out in this figure that the cap, while, of course, being somewhat larger than the fuse inserted therein, is larger in diameter than the diameter of the cylindrical opening provided within the two 75 jaws 13 and 14. As shown in this figure, besides completely filling the semi-cylindrical recesses, there will still be considerable portions at opposite sides of the cap, which will lie between the jaws. 80

The real crimping operation of the tool now begins. It will be understood that as the jaws are mounted for parallel movement, the pressure brought to bear upon the cap will be brought evenly in directly opposite 85 directions upon the upper and lower portions thereof, which will tend to cause the cap to be compressed tightly about the fuse upon each side of a diameter drawn through the fuse at right angles to the movement of 90 the jaws or vertically, as shown in Fig. 7. The excess of material which is shown to lie between the two jaws in Fig. 7 is squeezed outwardly in the form of plaits by continued movement of the jaws, as shown in Fig. 8. 95 The cap is now tightly compressed or crimped about the fuse and a plait is formed upon each side of the cap, thus taking up the excess of material and effectively securing 100 the cap to the fuse. The plane portions of the jaws adjacent the semi-cylindrical recesses will act upon these plaits to flatten them out, so that there will be no tendency 105 for them to spring apart and thus loosen the fuse within the cap.

It has been demonstrated that the parallel movement of the jaws is a very important feature in the successful operation of a tool of this kind. The evenly distributed and directly opposed pressures upon the opposite portions of the cap shown in Fig. 7 would not be obtained with any other movement such for instance as would be provided by the use of pivoted or "alligator" jaws. 110 There would be in the latter case a tendency to squeeze the surplus of metal toward the forward side of the cap, so that there would not be the taking up of the material in the form of plaits upon both sides of the cap. 115

Moreover, it will be apparent that by the provision of a stop for positioning the work, I have greatly increased the efficiency of operation of the tool. Instead of the user having to be particular to seat the work within the recesses in the jaws, he has only to insert the cap and fuse between the jaws and move them rearwardly until they come into contact with the stop, which operation will not require his attention. Moreover, in 120 the structure of the pin 22, I have provided 125

common means to serve as a stop for positioning the work and as one of the elements to lock the jaws in closed position. The positioning of the locking catch 26 upon the upper jaw 13 will be found to be highly desirable in that this catch is placed in convenient position for movement by the thumb of the operator, while the tool is grasped in his hand. To lock the jaws in closed position does not then require the use of the fingers of the hand in which the tool is not held.

While I have shown and described with particularity a preferred form of my invention, it is to be understood that it is not to be limited to the exact details shown, but is capable of many modifications and variations which will lie within the spirit of the invention and within the scope of the appended claims.

What I claim is:

1. The method of crimping a tubular casing about a fuse or the like, which comprises inserting the casing with the fuse therein between a pair of parallel jaw members having complementary recesses formed therein to receive the casing and simultaneously exerting pressure upon the upper and lower portions of the casing in directly opposite directions by moving said jaws bodily toward each other to cause the excess material of the casing to be pressed out evenly on both sides of the fuse in the form of plaits.

2. The method of compressing a cylindrical casing about a fuse or the like which comprises seating oppositely disposed portions of the same in recesses, of substantially semi-cylindrical shape, in the opposing surfaces of two oppositely disposed spaced parallel forwardly opening jaw members and then producing relative approaching movement of the jaws while maintaining their parallelism.

3. The method of crimping a tubular casing about a fuse or the like by forming plaits upon both sides thereof which comprises placing the casing between two parallel jaw members provided with complementary recesses to receive and compress the casing and exerting pressure upon it in directly opposite directions by moving said jaws bodily directly toward each other while maintaining their parallelism to force the excess metal of the casing into flat plaits at both sides of the fuse.

4. A tool for clamping a tubular casing about a fuse or the like, comprising a pair of pivoted handles, a pair of jaws pivoted to said handles and guided for parallel movement thereby, and presenting a forwardly opening throat, said jaws being provided with relatively large transverse recesses to receive portions of the casing at the upper and lower sides thereof, and having flat surfaces upon each side of said

grooves whereby pressure may be exerted on the casing in directly opposite directions by both jaws simultaneously.

5. A cap crimping tool, comprising a pair of pivoted handles and a pair of jaws operated thereby in parallel movement, each of said jaws being provided with a relatively large transverse groove or seat segmental in cross section to receive a portion of the cap, and with flat surfaces upon each side of said groove opposing similar flat surfaces on the other jaw whereby pressure may be exerted upon the cap in directly opposite directions and the excess metal therein forced out evenly upon both sides thereof, and pressed into plaits by the flat surface of the jaws adjacent the recesses.

6. A cap crimping tool, comprising a pair of pivoted handles and a pair of jaws operated thereby in parallel movements, each of said jaws being provided with a relatively large transverse groove or seat segmental in cross section to receive a portion of the cap, and with flat surfaces upon each side of said groove opposing similar flat surfaces on the other jaw, and a stop disposed at the rear of said recesses to position the work therein.

7. A hand tool comprising a pair of pivoted handle members, a pair of jaws operated thereby and common means for positioning the work between the jaws and locking the tool in closed position.

8. A hand tool comprising a pair of pivoted handle members, a pair of jaws operated thereby, a stop member for positioning the work between the jaws, and means cooperating with said stop member to lock said jaws in closed position.

9. A hand tool comprising a pair of pivoted handle members, a pair of jaws operated thereby, a stop member for positioning the work between the jaws, and a catch cooperating with said stop member to lock said jaws in closed position.

10. A hand tool comprising a pair of pivoted handle members, a pair of jaws operated thereby, a stop to position the work between the jaws and a sliding catch to engage said stop to lock the jaws in closed position.

11. A hand tool comprising a pair of pivoted handle members, a pair of jaws operated in parallel movement thereby, a pin upon one of said jaws and means to engage said pin to lock the jaws in closed position.

12. A hand tool comprising a pair of pivoted handle members, a pair of jaws operated in parallel movement thereby, a member, upon one jaw, projecting beyond the other jaw when the tool is closed, and means upon the second named jaw to engage said member to lock the tool in closed position.

13. A hand tool comprising a pair of pivoted handle members, a pair of jaws operated thereby, a pin upon one of said jaws,

the other jaw having an opening to receive said pin, the pin projecting through said opening and beyond the second named jaw when the tool is in closed position and means 5 to engage the projecting end of the pin to secure said jaws in closed position.

14. A hand tool comprising a pair of pivoted handle members, a pair of jaws operated thereby, a pin upon one of said jaws, 10 the other jaw having an opening to receive said pin, the pin projecting through said opening and beyond the second named jaw when the tool is in closed position and a catch upon the second named jaw to engage 15 the projecting end of the pin.

15. A hand tool comprising a pair of pivoted handle members, a pair of jaws operated thereby, a pin upon one of said jaws, the other jaw having an opening to receive 20 said pin, the pin projecting through said opening and beyond the second named jaw when the tool is in closed position and a catch upon the second named jaw slideable into position to engage the projecting end 25 of the pin.

16. A hand tool comprising a pair of pivoted handle members, a pair of jaws operated thereby, a pin upon one of said jaws, the other jaw having an opening to receive

said pin, the pin projecting through said 30 opening and beyond the second named jaw when the tool is in closed position, the projecting end of said pin having a recess there- in and a catch to engage in said recess to lock the jaws in closed position. 35

17. A hand tool comprising a pair of pivoted handle members, jaws operated in parallel movement thereby, a pin secured to one of said jaws, a sliding catch mounted upon the other, said catch being movable to engage 40 said pin to lock the jaws in closed position.

18. A cap crimping tool, comprising a pair of pivoted handles and a pair of jaws operated thereby in parallel movements, 45 each of said jaws being provided with a relatively large transverse groove or seat segmental in cross section to receive a portion of the cap, and with flat surfaces upon each side of said groove opposing similar 50 flat surfaces on the other jaw, and a stop pin upon the face of one jaw extending into an opening in the other jaw to position the work longitudinally of the tool.

In witness whereof, I have hereunto set 55 my hand this 2nd day of April, 1921.

WILLIAM A. BERNARD.
